US00D688224S

(12) United States Design Patent
Kim et al.

(10) Patent No.: US D688,224 S
(45) Date of Patent: * Aug. 20, 2013

(54) MOBILE TERMINAL

(75) Inventors: Kuk-Hwan Kim, Seoul (KR);
Seog-Guen Kim, Seoul (KR); Tae-Ho Kim, Yongin-Si (KR)

(73) Assignee: Samsung Electronics Co., Ltd.,
Suwon-si (KR)

() Term: 14 Years

(21) Appl. No.: 29/427,659

(22) Filed: Jul. 20, 2012

(30) Foreign Application Priority Data

Mar. 6, 2012 (KR) 30-2012-0010558
